Primary Examiner — Rhea Shields*(74) Attorney, Agent, or Firm* — Perkins Coie LP(57) **CLAIM**

The ornamental design for a combined baby brush and comb, as shown and described.

DESCRIPTION

FIG. 1 is a perspective view of the combined baby brush and comb, showing my new design;

FIG. 2 is a front view thereof;

FIG. 3 is a back view thereof;

FIG. 4 is a right side view thereof;

FIG. 5 is a left side view thereof;

FIG. 6 is a top plan view thereof; and,

FIG. 7 is a bottom plan view thereof.

In the drawings, the broken lines are for the purpose of illustrating portions of the combination baby brush and comb that forms no part of the claimed design.

1 Claim, 4 Drawing Sheets(56)
